UNITED STATES PATENT OFFICE

HARVEY S. HEADLAND, OF PITTSBURGH, PENNSYLVANIA

ILLUMINATED CANOPY FOR CASKET ILLUMINATION

Application filed July 7, 1930. Serial No. 466,207.

This invention relates to a novel illuminated canopy for caskets and has as one of its objects to provide a novel means whereby a canopy may be most effectually draped at one side of a casket the lid of which has been removed or swung to open position and beneath and in rear of which canopy electric light bulbs will be arranged so as to illuminate the deceased and the interior of the casket.

Another object of the invention is to provide a device for the purpose stated which may be readily adjusted as regards its length, so that it may be readily mounted upon caskets of different sizes.

Another object of the invention is to so construct the canopy supporting frame structure of the device so that expansion and contraction of the structure may be effected without any manipulation of any mechanical adjusting means.

Another object of the invention is to provide a novel means for mounting the device upon one side wall of the casket body and which means will be so constructed that its engaging portions will possess sufficient pliability to adapt them to be spaced at various distances apart and bent or flexed to adapt them to engage the inner and outer sides of the wall of the casket in a manner to substantially conform to the shape thereof, thereby avoiding any likelihood of mutilation of the finish of the casket.

This invention also consists in certain other features of construction and in the combination and arrangement of the several parts, to be hereinafter fully described, illustrated in the accompanying drawings, and specifically pointed out in the appended claims, it being understood of course that minor changes may be made so long as they fall within the scope of the claims.

In describing my invention in detail, reference will be had to the accompanying drawings wherein like characters denote like or corresponding parts throughout the several views, and in which:

Figure 1 is a view in elevation of the frame structure embodying the invention, the canopy being omitted from this view to better illustrate the invention.

Figure 2 is a similar view looking at the reinforced side of the structure and illustrating the manner in which the canopy is connected therewith.

Figure 3 is a group view illustrating the manner in which two of the frame members, which are expandable and contractible, may be assembled.

Figure 4 is a vertical front to rear sectional view on the line 4—4 of Figure 2.

Figure 5 is a similar view on the line 5—5 of Figure 2.

Figure 6 is a perspective view of one of the supporting brackets of the frame structure.

The frame structure preferably consists in a combination of a telescopic frame unit and a lazy tong unit and means for so connecting these units that the two may be simultaneously expanded or contracted. The lazy tong unit comprises two side bars indicated in general by the numeral 1 and these bars are preferably formed with longitudinal slots 2. The lazy tong which constitutes a part of this unit comprises the usual assemblage of a series of intersecting links 3 which are connected preferably by hollow pivots 4 at their points of mutual intersection and also the adjacent links of adjacent pairs are connected at their upper ends by hollow or tubular pivots 5, and the lower ends of the links may be connected by solid pivots 6. The upper ends of the upwardly inclined links at the ends of the series of links are pivotally connected as at 7 with the upper ends of the respective bars 1, and pivots 8 are secured through the lower ends of the downwardly inclined endmost links of the series and slideable through the slots 2 in the respective arms. Due to this construction and arrangement of parts, it will be evident that the bars 1 may be bodily adjusted toward and from each other by an expansion or contraction of the lazy tong unit.

The telescopic unit is shown in detail in Figure 3 of the drawings and comprises two telescopically fitted members indicated one by the numeral 9, and the other by the numeral 10. These telescopic sections are pref-

erably of rectangular tubular form and the outer end of each section is bent at right angles as indicated by the numeral 11 and in order that the sections may be readily assembled with the lazy tong unit, small right angle brackets 12 are mounted upon two of the pivots 6, and the tubular right angle ends 11 of the telescopic unit are adapted to be fitted to these brackets and, due to the pliable nature of the sections 9 and 10, an expansion or contraction of the lazy tong unit will effect corresponding expansion or contraction of the telescopic unit. The invention contemplates a novel form of bracket for supporting the structure above described, and other parts thereof to be presently explained, at one side of the casket body, and one of these brackets is illustrated in Figure 6 in detail. The bracket which is indicated in general by the numeral 13, comprises two leaves 14 of soft lead, each of which leaves is provided with a sheath or covering 15 of felt or any other flexible fabric or similar material found desirable. The two leaves are arranged in superposed relation as shown in Figure 6 and also as shown in Figure 5, and these leaves are preferably united against relative separation, near one end of the assemblage but the remaining portions of the leaves may be bent as indicated by the numeral 16, to any desired arcuate contour to provide spaced gripping portions 17 which may be caused to fit against the inner and outer sides of one side wall of the casket body when the brackets are arranged in place upon the said wall.

Each leaf 14, at its end which is united with the other leaf, is provided with a tongue extending at right angles therefrom, and these tongues are indicated by the numeral 18 and extend in opposite directions from the assemblage as a whole and, in assembling the brackets with the frame structure previously described, the tongues 18 are passed through the spaces between two companion or associated pairs of the lazy tong links, and as shown in Figure 5 and for a purpose which will presently be explained, a nipple 19 of soft rubber is fitted onto the downwardly extending one of the tongues 18.

The numeral 20 indicates a canopy which is draped over the frame structure and held in place thereon by any suitable means, it being practicable to extend a rod 21 between two lines of stitching 22 in the drapery, which rod may be mounted at its ends upon hooks 23 projecting over the small plates 24 mounted at the upper ends of the side members 1, 60 the rod 21 preferably consisting of two telescopically assembled sections as shown in Figures 1 and 2.

In order that the remains in the casket may be suitably and properly illuminated 65 without the source of illumination being vis-

ible to those attending the funeral, a number of brackets 25 are mounted upon certain of the pivots 5 and each bracket supports an electric light bulb socket 26 in which is fitted a light bulb 27 and conductor wires 28 are led from the sockets and, as shown in Figures 1 and 2 of the drawings, back and forth through the hollow pivots 4 and 5 throughout the series of links of the lazy tong unit, these conductor wires 28 being led first to a switch 29 and then to a plug 30 which may be inserted in any ordinary house electric socket.

What I claim is:

1. A casket canopy comprising attaching bracket members each having relatively spaced portions to fit over the upper edge of a casket wall, a longitudinally expansible and contractible frame structure supported by the brackets, and a canopy draped over the frame member. 80

2. A casket canopy comprising attaching bracket members each having relatively spaced portions to fit over the upper edge of the casket wall, a longitudinally expansible and contractible frame structure supported by the brackets, the frame structure comprising a lazy tong unit, and a telescopic bow unit connected at the ends of its members with the lazy tong unit, and a canopy draped over the units. 90

3. A casket canopy comprising attaching bracket members each having relatively spaced portions to fit over the upper edge of a casket wall, a longitudinally expansible and contractible frame structure supported by the brackets, the frame structure comprising a lazy tong unit, and a telescopic bow unit connected at the ends of its members with the lazy tong unit, the connection between the units comprising tongues extending forwardly from the ends of the lazy tong unit, and sockets at the ends of the telescopic unit in which the tongues are fitted, and a canopy draped over the units. 100

4. A casket canopy comprising attaching bracket members each having relatively spaced portions to fit over the edge of a casket wall, a longitudinally expansible and contractible frame structure supported by the brackets, the frame structure comprising a lazy tong unit, the lazy tong unit comprising upright bars, a series of crossed links pivotally connected at their points of intersection and at their relatively adjacent ends, the upper ends of the upwardly inclined links at the ends of the series of links being pivotally connected to the upper ends of the respective upright bars and the lower ends of the downwardly inclined links at the ends of the series of links being pivotally and slidably connected with the said upright bars, 110

and a telescopic bow unit connected at the ends of its members with the lazy tong unit, and a canopy draped over the units. 120

5. A casket canopy comprising attaching bracket members each having relatively spaced pliable portions to fit over the upper edge of a casket wall, a longitudinally expandible and contractible frame structure supported by the brackets, and a canopy draped over the frame member.

6. A casket canopy comprising attaching bracket members each having relatively spaced portions to fit over the upper edge of a casket wall, a longitudinally expandible and contractible frame structure supported between brackets and adapted to carry an illuminating means, the frame structure comprising a lazy tong unit, and a telescopic bow unit connected at the ends of its members with the lazy tong unit, each bracket member having oppositely extending tongues at one end engageable between the links of the lazy tong unit, and one of the tongues being provided with a cushioning means and a canopy draped over the units.

In testimony whereof I affix my signature.
